SYNCHRONIZING SIGNAL GENERATOR

Hugh C. Ressler, West Brighton, Staten Island,
N. Y., assignor to Faximile, Inc., New York,
N. Y., a corporation of Delaware

Application October 25, 1940, Serial No. 362,775

5 Claims. (Cl. 178—69.5)

The present invention concerns synchronizing and, in particular, the generation of synchronizing signals in a facsimile transmitter or the like.

One object of the present invention is to provide a method of and means for generating a synchronizing impulse of improved characteristics.

A further object is to provide simple means for generating a highly accurate synchronizing signal.

A still further object is to provide a method of and means for switching a synchronizing signal into a signal channel without altering in any way the shape or duration of the signal.

These and other objects will be apparent from the detailed description of the invention given in connection with the various figures of the drawing.

In the drawing:

Fig. 1 shows a facsimile transmitter circuit embodying one form of the present invention.

Fig. 2 shows a diagram useful in explaining the operation of the invention as shown in Fig. 1.

Fig. 3 shows a second diagram useful in explaining the operation of the invention as shown in Fig. 1.

Fig. 4 shows a third diagram illustrating the operation of the invention.

The transmission of facsimile by wire or radio is generally accomplished by scanning a subject to be transmitted line by line by means of a point of light, picking up the reflected light from the subject in a photo-electric cell and modulating a sub-carrier signal with the amplified output of the photo-electric cell to form a modulated picture signal. This modulated picture signal may be transmitted over wire lines to a receiving point, or it may be used to modulate a radio frequency carrier which is then radiated, to be picked up at the receiver. At the receiver the modulated signal is rectified and the rectified current is utilized to actuate a recorder to reproduce the facsimile image.

In the process just described, it is important that the transmitting and receiving scanners operate in synchronism and in phase. The accuracy of the synchronization from line to line, to a large degree, determines the accuracy and usable detail in the reproduced image.

One satisfactory method of synchronizing consists in leaving a space in the picture signal between successive scanning lines and inserting in this space a synchronizing or timing signal. A square topped impulse, which after modulation becomes a group of constant amplitude sub-carrier frequency signals, forms a convenient syn-

chronizing signal. The accuracy in time at which this impulse starts and/or ends determines the accuracy with which the receiver may be timed when utilizing this signal.

5 In the past this synchronizing impulse has been produced by closing an electrical circuit between the source of sub-carrier signal and the transmission circuit for an interval equal to the desired duration of the synchronizing impulse. A commutator segment attached to the transmitter scanner drum shaft, a cam operated switch or a relay has been used to close the electrical circuit. It has been found that a high degree of accuracy is difficult to obtain by any of these prior means. 10 It has also been found that since these means close current carrying circuits, transients are produced which disturb the system and detract from the accuracy of synchronization.

The present invention concerns a system in 20 which highly accurate timing impulses are produced by electronic means. These impulses are so formed that they may be switched into and out of the transmission circuit when no current is flowing in the source. In this way the accuracy of the synchronizing impulses may be predetermined and it is not affected by the switching operation. In addition, the switching at zero current prevents the production of transients.

25 Fig. 1 shows a facsimile transmitter embodying one form of the present invention. Fig. 1 shows a 60 cycle synchronous motor 4 connected to a source of 60 cycle power by means of leads 9 and 10. Motor 4 drives transmitter pick-up drum 6 thru a suitable reducing gear box 5. Gear box 5 may, for instance, transform a motor shaft speed of 3600 revolutions per minute to a drum shaft speed of 200 revolutions per minute, a reduction of 18 to 1. Drum 6 carries a commutator 7 provided with shorting bar 8 grounded by brush 2 in contact with conducting ring 8' also connected to bar 8. Brushes 1 and 3 are grounded whenever they contact bar 8. Subject matter on the surface of drum 6 is scanned by directing a 30 spot of light from lamp filament 11, thru lens 12 to the subject matter, and picking up the reflected light by means of lens 13, directed to photo-electric cell 14. The output of photo-electric cell 14 is fed to the amplifier and sub-carrier modulator 15. A source of sub-carrier signals 19 is also fed to amplifier-modulator 15 and the output of this amplifier-modulator 15 is fed to the radio modulator 16 from which the final signals are fed to antenna 17 and ground 18. 35 In order to generate synchronizing impulses,

60 cycle current is fed to diodes 23 and 23' by means of a transformer having primary 20 connected to the 60 cycle power source and secondary 21 connected to diode 23 and secondary 22 connected to diode 23'. One side of secondary 21 is connected to cathode 24 of diode 23 and the other side is connected to one end of diode load resistor 26. Anode 25 of diode 23 is connected to the other end of diode load resistor 26. During the negative part of the cycle of the 60 cycle input, diode 23 will pass current, making the anode end of resistor 26 negative with respect to its other end. The anode end of resistor 26 is connected to grid 32 of triode 30, and the other end to cathode 31. Plate 33 is connected to a source of plate potential 53. During the intervals of diode current flow, grid 32 receives a negative bias with respect to cathode 31 and the cathode current of the tube 30 is cut-off. During the other half cycle of the 60 cycle wave, no current is passed by diode 23 and a steady cathode current flows in tube 30. Hence, across resistor 38, connected between cathode 31 and ground 18, will appear rectangular voltage impulses corresponding to positive half cycles of the 60 cycle current, as shown at *a* in Fig. 2.

In a similar manner but with reversed polarity, diode 23' passes current from secondary 22 from cathode 27 to anode 28, setting up negative half cycle impulses across resistor 29. Tube 34 has its grid connected to one end of resistor 29 and its cathode connected to the other end. Plate 37 of tube 34 is connected to plate potential source 53. Thus current flows in resistor 39 on half cycles alternating with the half cycles during which current flows in resistor 38. The voltage drop across resistor 39 is represented by the impulses shown at *b* in Fig. 2. The minimum values of curves *a* and *b* is due to bias from either resistor 39 or 38 feeding back to the other thru the isolating resistors 40 and 41. The sum of *a* and *b* of Fig. 2, as shown at *m* in Fig. 3, is applied to cathodes 46 and 49 of diodes 45 and 48 thru isolating resistors 40 and 41, lead 44 and secondary 43. As long as cathodes 46 and 49 receive a positive bias of more than a critical value, as shown by dotted lines, *t*, *x* and *y*, they will not pass current. Sub-carrier voltage is applied to cathodes 46 and 49 by means of transformer 42-43, but it is passed to plates 47 and 50, primary 51, secondary 52 and thus to radio modulator 16 only when the positive bias is removed from cathodes 46 and 49. This bias is removed during predetermined intervals, in order to pass impulses of sub-carrier signals to modulator 16, to provide synchronizing signals. Brush 1 grounds at the instant it touches bar 8, shorting resistor 39 and dropping its voltage to zero. This is shown where curve *b* of Fig. 2 intersects vertical line *c*. Tubes 45 and 48 are at cut-off when this shorting takes place, due to the positive bias from resistor 39, as shown by the intersection of curve *a* and vertical line *C* in Fig. 2. At about $\frac{1}{240}$ of a second later, curve *a* drops to zero at *h* in Fig. 2. Since resistor 39 is grounded, the impulse of 60 cycle voltage shown dotted in curve *b* of Fig. 2 is prevented from reaching diodes 45 and 48. About $\frac{1}{240}$ of a second later brush 3 grounds, shorting resistor 38 at a time corresponding to line *d* in Fig. 2. No bias voltage exists in resistor 39 at this instant, since it is still shorted out. Brush 1 opens at a time corresponding to *f* in Fig. 2. Brush 3 remains grounded until a time corresponding to *g* of Fig. 2, and thus the dotted impulse of curve *a* is prevented from reaching diodes 75

45 and 48. At *g*, diodes 45 and 48 are again at cut-off, due to the drop across resistor 39. It will be seen that an interval of zero bias extending from *h* to *k* in Fig. 2 is produced and diodes 45 and 48 are permitted to pass an impulse of sub-carrier voltage for this interval. It will also be seen that the duration of this impulse is accurately determined by the 60 cycle half wave impulses and is not affected by the time at which brushes 1 and 3 close and open. Thus, an electrical impulse is produced for synchronizing purposes, the duration of which is electrically determined, even though it is mechanically switched. The accuracy of the switch operation does not affect the duration of the impulse. The width and angle of commutator segment 8 may be varied to give any desired length of impulse in multiples of a half cycle of the input alternating current. Also, a single half cycle duration impulse may be generated by omitting one of diodes 23 or 23' and their associated circuits.

The bias on diodes 45 and 48 is shown in Fig. 3. Cut-off is removed, as described above, for an accurate and electrically timed $\frac{1}{240}$ of a second from *h* to *k*. During this interval, sub-carrier signals are passed by diodes 45 and 48 into the radio modulator and transmitter to produce a synchronizing impulse to be transmitted along with the picture signals. If the synchronizing impulse is produced between picture lines, a portion of a typical modulated sub-carrier signal will be as shown in Fig. 4, where *n n'* and *s s'* represent picture signals and *p p'* represents the synchronizing signal.

The present system eliminates synchronizing signal switching transients, since the switching brushes operate, while diodes 45 and 48 are at cut-off.

The present description has shown a system operating from a 60 cycle power line, but it will be evident that other frequencies may be used without departing from the invention.

While only a single embodiment of the present invention has been shown and described, many modifications will be apparent to those skilled in the art within the spirit and scope of the invention, as set forth in the appended claims.

What is claimed is:

1. In a synchronizing signal generator, means for generating a series of spaced impulses, means for generating a series of complementary impulses, means for periodically removing an impulse from said first series, means for removing an adjacent impulse from said second series, means for combining said first series and said second series to provide a substantially constant signal having periodic gaps, and means for generating a synchronizing signal conforming to said gaps.

2. In a synchronous signal generator, means for generating two groups of complementary periodic signals, means for reducing the instantaneous value of one of said groups to zero for a predetermined interval, and means for starting a synchronizing impulse during said interval whereby transients are substantially eliminated from said synchronizing impulse.

3. In a facsimile synchronizing signal generator, the combination of, a source of alternating current of predetermined frequency, a circuit for passing positive portions and cutting-off negative portions of a current derived from said source, a circuit for passing in reversed polarity negative portions and cutting-off positive portions of said derived current, a circuit for combining both of

said passed current portions to form a substantially constant current, a synchronous switch driven from said alternating current for cutting-out predetermined half cycles of one of said passed currents phased to close and open between half cycles of one of said passed currents to form an electrically timed synchronizing signal gap in said substantially constant current.

4. In a facsimile synchronizing signal generator, the combination of, a source of alternating current of predetermined substantially constant frequency, a circuit for passing positive portions and cutting-off negative portions of a current derived from said source, a circuit for passing, in reversed polarity, negative portions and cutting-off positive portions of said derived current, a circuit for combining both of said passed current portions to form a substantially constant current, a pair of synchronous switches operated from said alternating current for cutting-out predetermined adjacent half cycles of said passed currents phased to close and open one circuit between half cycles of one of said passed currents

and to close and open another circuit between half cycles of the other of said passed currents adjacent to said first half cycles to form an electrically timed synchronizing signal gap in said substantially constant current equal in duration to one cycle of said alternating current.

5. In a timed impulse generator, the combination of, a source of alternating current, means for deriving from said alternating current a series of unidirectional impulses corresponding to half cycles of one polarity, means for deriving from said alternating current a second series of unidirectional impulses corresponding to half cycles of the other polarity, means for periodically cutting out an adjacent impulse of each of said series operating between impulses of each series, means to combine said impulses to form a substantially constant current interrupted for electrically determined periodic intervals to form 10 a synchronizing gap, and means to generate a synchronizing impulse substantially equal to said gap.
